(57) CLAIM

The ornamental design for a mastectomy pillow, as shown and described.

DESCRIPTION

FIG. 1 is a front right perspective view of a mastectomy pillow showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a left side view showing the mastectomy pillow in an environment of use.

Broken lines in the drawings depict portions of the mastectomy pillow that form no part of the claimed design. The broken lines depicting a person in FIG. 8 are included for the purpose of illustrating environment and forms no part of the claimed design.

1 Claim, 8 Drawing Sheets
